CLAIM

The ornamental design for a forehead mask, as shown and described.

DESCRIPTION

FIG. 1 is a perspective view of a forehead mask;
FIG. 2 is a front view thereof;
FIG. 3 is a rear view thereof;
FIG. 4 is a right view thereof;
FIG. 5 is a left view thereof;
FIG. 6 is a top view thereof;
FIG. 7 is a bottom view thereof;
FIG. 8 is an exploded perspective view thereof;
FIG. 9 is a perspective view thereof, shown in an environment of use; and,
FIG. 10 is a perspective view thereof, shown in another environment of use.
In the drawings, the broken lines represent environmental subject matter and form no part of the claimed design.
